E. FELTMAN,
LIFTING AND SWINGING GATE,
APPLICATION FILED JULY 17, 1916.

1,257,334.

Patented Feb. 26, 1918.

FIG. 1.

FIG. 2.

Edward Feltman

Inventor

By *Geo. P. Kimmel*

Attorney

UNITED STATES PATENT OFFICE.

EDWARD FELTMAN, OF OTTAWA, OHIO.

LIFTING AND SWINGING GATE.

1,257,334.

Specification of Letters Patent. Patented Feb. 26, 1918.

Application filed July 17, 1916. Serial No. 109,674.

To all whom it may concern:

Be it known that I, EDWARD FELTMAN, a citizen of the United States, and resident of Ottawa, in the county of Putnam and State 5 of Ohio, have invented certain new and useful Improvements in Lifting and Swinging Gates, of which the following is a specification.

The present invention relates to fences and 10 more particularly to new and useful improvements in lifting and swinging gates, the primary object of my invention being to provide an improved type of swinging gate having means associated therewith for raising the gate before swinging to permit the 15 same to escape obstructions such as snow and ice in a roadway.

Another object of my invention is to provide a gate of the class described which is 20 simple in construction, strong and durable and cheap to manufacture and install.

A further object of my invention is to provide a mechanism of the class described which may be readily applied to various 25 types of gates now in use without materially altering the gate structure.

Other objects and advantages to be derived from the use of my improved lifting and swinging gate will appear from the following detail description and the claim, taken with an inspection of the accompanying drawing, in which:

Figure 1 is a side elevational view of a gate embodying the improvements of my invention;

Fig. 2 is a detached perspective view of the lifting mechanism; and

Fig. 3 is a fragmental end view of the latching mechanism for holding the gate in 40 lifted position.

Referring more particularly to the drawing, wherein similar characters of reference designate like and corresponding parts throughout the various views, 1 and 2 indicate fence posts of the usual type. A gate is designated 3 and is composed of a plurality of slats 4 supported by standards 5, 6 and 7. Diagonal braces 8 are provided on the gate.

50 The hinge means of my invention includes a plurality of bearing brackets 9, 10 and 11 carried on the post 2, said brackets supporting a vertically arranged bearing rod 12. A plate 13 is bolted as at 14 to the standard 7 of the gate, said plate having loops 15 on its opposite end for engagement with said rod

12. The plate 13 and the loops 15 thereof serve as a hinge for the gate, the loops in normal position resting upon the brackets 10 and 11.

60 The raising mechanism of my invention includes a lever 16 arranged diagonally across the face of the gate 3, said lever being pivoted on a lateral extension 17 of the rod 12, a cotter pin 18 serving to prevent displacement of said lever. A guiding bracket 19 embraces the lever 16 at a point intermediate its ends, said bracket having apertures 20 in the free ends thereof through which bolts 21 or the like fastening means are 65 adapted to be engaged, said bracket member being mounted on the standard 6 of the gate. The free end of the lever 16 is adapted to engage a ratchet bar 22 carried by the gate, arranged diagonally thereof adjacent the free 70 end of the gate. The lever 16 is recessed as at 23 to more securely engage the teeth of the ratchet bar 22.

75 A strap 24 is carried by the lever 16, said strap having the free ends thereof spaced as 80 at 25, to receive the hook portion 26 of a lifting rod 27, the lower end of said rod being formed with a similar hook 28 for engagement with a strap 29, said strap 29 being similar to the strap 24. It will be seen that 85 when the lever is raised the lifting rod 27 will cause the gate to be raised, the loop 15 sliding on the rod 12. The gate is maintained in raised position by virtue of the engagement of the lever 16 with the ratchet 90 bar 22. Of course, the lever is inherently resilient permitting its disengagement from the ratchet teeth to lower the gate. A conventional form of latch 30 is provided on the post 1, said latch being arranged whereby to 95 lock the gate at any point in its vertical movement. The gate is permitted to swing at any point in its vertical movement owing to the slidable and rotatable engagement of the loop 15 with said rod 12. Thus it will 100 be seen that in the provision of my improved gate I have afforded means for raising a gate to escape obstruction and to render more efficient gates of this class.

105 From the above description taken in connection with the accompanying drawing, it is thought that a clear and comprehensive understanding of the construction, operation and advantages of my invention may be had, and while I have shown and described the 110 device as embodying a specific structure, I desire that it be understood that such

changes may be made in said structure as do not depart from the spirit and scope of the invention as claimed.

Having thus fully described my invention, 5 what I claim as new and desire to secure by Letters Patent, is:—

The combination with a gate post having a vertically disposed spaced bar extending parallel therewith, a gate slidably and 10 swingably mounted on said bar, a lever extending diagonally across said gate, one end of said lever being pivotally mounted on the upper end of the vertical bar, a guiding bracket for said lever mounted on the gate 15 and rigidly secured thereto, a strap member

carried by the lever intermediate its ends, the free ends of said strap being straight, a second strap carried by the lower edge of the gate, a link member, hook portions formed on the ends of said link, one hook 20 adapted to be received between the straight ends of the first mentioned strap and the opposite hook being adapted to be retained in the second mentioned strap, and means on said gate for retaining the lever in various 25 adjusted positions.

In testimony whereof, I affix my signature hereto.

EDWARD FELTMAN.
